DESIGN FOR A COMBINATION MEAT TENDERER AND FOOD CHOPPER

Russell C. Burdge, Muncie, Ind.

Application January 3, 1935, Serial No. 54,706

Term of patent 14 years

To all whom it may concern:

Be it known that I, Russell C. Burdge, a citizen of the United States of America, residing at Muncie, in the county of Delaware and State of Indiana, have invented a new, original, and ornamental Design for a Combination Meat Tenderer and Food Chopper, of which the following is a specification, reference being had to the accompanying drawing, forming part thereof.

I claim:—

The ornamental design for a combination meat tenderer and food chopper, as shown.

RUSSELL C. BURDGE.
